UNITED STATES PATENT OFFICE.

LAWRENCE P. MARCELL, OF SOUTH PORCUPINE, CANADA.

LUBRICATOR FOR COMPRESSED-AIR MACHINES.

Application filed December 28, 1925. Serial No. 78,017.

This invention relates to an improved lubricating device.

The primary object of this invention is the provision of an improved lubricator for compressed air machines, which is capable of supplying lubricants to the operating parts of the machine, proportionate to the speed at which the machine is operated.

An important object of the invention is the provision of an improved lubricator for machines propelled by compressed air, capable of efficiently and automatically lubricating parts of the machinery, with a continuous feed, regulated in quantity according to the speed at which the machine is operated.

A further object of this invention is the provision of a lubricator of the above described type which is adaptable for use in air lines supplying air pressure operated machines, without altering the construction of the machines or hindering their normal operation.

Further objects and advantages of this invention will be apparent during the course of the following detailed description.

In the accompanying drawing, forming a part of this specification, and wherein similar reference characters designate corresponding parts throughout the several views,

Figure 1 is a transverse sectional view taken thru the improved lubricating device showing the relation of the pump structure thereof to the air conduit or passageway.

Figure 2 is a horizontal sectional view taken substantially on the line 2--2 of the improved lubricator, showing its relation in an air line.

Figure 3 is a side elevation of a spirally grooved spindle included as a part of the motor or pump of the improved lubricator.

In the drawing, wherein for the purpose of illustration is shown only a preferred embodiment of this invention, the letter A may generally designate the device which may comprise a housing B consisting of an oil reservoir casing C and air conduit or casing D. The improved motor or pump F is operatively positioned in the housing B in cooperation with both the oil or lubricant casing C and air conduit casing portion D, for the supplying of lubricant from the casing C to the casing D, proportionate

to the speed at which the machine upon which the lubricator is mounted, is operated.

The improved lubricator is adapted to be placed in an air line leading to the machine which is to be lubricated, and this air line may include the spaced tubular sections G and H, as a part of the air line or conduit, having respective passageways 10 and 11 therethrough.

These sections G and H are screw threaded at their ends, adapted for detachably seating in the screw threaded socket ends 12 and 13 of the casing portion D of the housing A, to align the passageways 10 and 11 with the longitudinally extending passageway 15 of the casing portion D, to provide a single conduit along which the compressed air travels, from a suitable source to the machine which is adapted to be lubricated.

The casing portions C and D of the housing B are shown integral, altho they may be separable. The casing portion D of the housing B has a lateral offset 20, providing a chamber 21 communicating with but offset from the conduit way 15, within which the propeller wheel 22 of the motor or pump F is adapted to operate.

The motor or pump F in the main comprises the wheel 22, which might appropriately be termed the runner wheel, and it is suitably keyed upon the upper reduced end 25 of a grooved spindle 26, which is vertically positioned with its upper end in the chamber 21 and its lower end extending downwardly into the reservoir 27 of the lubricating casing C. The spindle 26 is provided with a bushing sleeve 30 of any approved material, which is mounted in a suitable opening 31 vertically provided in the wall 32 between the casings C and D. The lower end of this bushing 30 extends into the upper portion of the compartment 27, and the upper end of the bushing 30 is annularly flanged at 33, outwardly, to provide a shoulder which rests upon the bottom surface of the runner chamber 21.

The runner or motor wheel 22 is positioned upon a horizontal plane for rotation on a vertical axis, and the same includes the hub portion 38 which is keyed, as above mentioned to the reduced end 25 of the spindle 26, and the blades 39 of said wheel 22 are preferably radially disposed, and extend into one side of the conduit passageway 15, so

that during rotation of the wheel 22 the outer edges of said blades 39 will not pass across the center line of the conduit passageway 15, and thus do not interfere with the travel of compressed air from the source past the lubricator to the machine which is to be operated. A suitable bearing is provided between the motor wheel 22 and the top of the bushing 30, comprising a series of ball bearings 40 placed between the top surface of the bushing 30 and the lower surface of the runner or wheel 22; the wheel 22 and the bushing 30 being so shaped as to form upper and lower races for these anti-friction bearings, to prevent their displacement. This bearing arrangement takes the vertical thrust incident to operation of the pump or motor F.

Immediately above the pump F, in the upper portion of the offset 20 and the casing portion D, an internally screw threaded opening 45 is provided, as an entrance to the compartment 21, and which is sufficiently large to permit the detachment of all parts of the motor F including the bushings and bearings therefor. Below this opening 45 an upwardly facing shoulder 48 is provided, and a centering cap or bearing 50 is adapted to be inserted thru the opening 45, the same having an annular margin portion which rests upon the annular shoulder 48, to support the cap 50 in position. A standard screw threaded plug 55 is screw threaded in the opening 45 to clamp the centering cap 50 rigid.

The upper end of the spindle reduced portion 25 projects above the top surface of the motor wheel 22, and has a step bearing in the cap 50, the latter being recessed to receive the upper end 25 of the grooved spindle 26. A ball bearing device 57 may be supported by the cap 50, including inner and outer races with ball bearings therebetween; the inner race bearing against the loose end 25 of the spindle 26, as is illustrated in Figure 1 of the drawings. This supports the spindle 26 in a very stable manner, to prevent lateral vibration, and support the wheel 22 in a horizontal plane, against lateral vibration incident to operation thereof. It is to be noted that the upper end of the centering cap 50 may be provided with a reduced polygonal shank, adapted to be received in the recess of the clamping plug 55.

A riser barrel or sleeve 60 is received in a socket provided in the lower end of the bushing 30, and has a passageway 61 therein thru which the spindle 26 snugly extends for rotation, it being understood that the sleeve 60 is stationary. The lower end of the sleeve or barrel 60 supports a filtering cap 62 of fine mesh copper wire gauze, which prevents foreign particles from entering the groove of the elevating spindle 26.

The oil casing C includes the reservoir 27

as above mentioned, and the bottom wall 65 thereof is provided with a suitable screw threaded drain opening 66, detachably receiving a cap 67 recessed at 68 to provide a sump into which the lower screened end of the pump extends to receive lubricant. In the top wall 32 of the lubricating casing C a duct 70 is provided which communicates the motor compartment 21 with the reservoir 27 in order to equalize air pressure between the oil chamber and runner chamber. A filler cap 75 is provided on the lubricating casing C, to one side of the motor, as a means of filling the reservoir or compartment 27.

From the foregoing description the operation of the invention will be apparent. As the air flows along the air line, in the direction indicated by the arrow in Figure 2, the air will impinge against the inwardly projecting blades 39, and cause a revolution of the wheel 22, and a corresponding revolution of the spindle 26. The spindle 26 is provided with a spiral groove 80 therein, from end to end, spiraling about the spindle 26 in one direction, and an oppositely disposed spiral groove 82 which spirals in the opposite direction, so that notwithstanding the direction in which the spindle is rotated about its axis, the same will cause to be elevated a predetermined amount of lubricant from the oil reservoir 27 into the passageway 15 of the conduit casing portion D. It is to be particularly noted that the spindle and pump structure at no portion thereof are in direct line with the traveling air, except the slightly inwardly projecting portions of the blades 39, which do not act to any material extent in offering resistance to the air travel, and so that the efficiency of operation of the machine is not impaired by reason of the placing of the lubricator A in the air line. This is not true of certain types of lubricators which seek to automatically lubricate proportionate to the speed of the machine. There is one type of lubricator which seeks this result, but which embodies a motor which in itself constitutes a portion of the conduit for the air travel. The practical results of such structure is that oil will leak out of all proportions into the air line; the resistance offered is so much that the air is slowed to a material extent; the friction is excessive; loose particles of foreign materials enter the bearings; and centrifugal force acts to prevent the lubricant from entering the air line or conduit thereof, rather than permitting its entrance. In the improved lubricator herein shown and described, however, the oil or lubricant is efficiently elevated by the spindle 26, within the barrel riser 60, in a vertical path, and it enters the offset inner chamber 21, passing between the bushing 30 and the runner wheel 22, and is laterally drawn into the air passageway 15; centrifugal force aiding in

flowing of this lubricant into the passageway 15. It is of course apparent that the only portion of the lubricator entering the conduit 15 to obstruct the passage of air is the outer ends of the blades 39, and these do not slow the air to any material extent, and they offer very little resistance. The friction incident to operation is practically negligible.

It is noteworthy that the motor parts 10 of the lubricator are accessible at all times, and may be readily detached and replaced, without inconvenience.

Various changes in the shape, size, and arrangement of parts may be made to the form 15 of invention herein shown and described, without departing from the spirit of this invention and the scope of the claims.

I claim:

1. In a lubricator of the class described 20 the combination of a conduit having a passageway for flow of compressed air therealong, a casing having a lubricant receiving compartment therein, and pump means for drawing lubricant from the compartment 25 into the compressed air passageway including a rotary wheel the axis of which is arranged substantially transversely of the run of the compressed air passageway, said wheel including blades extending transversely into the compressed air passageway.
2. In a lubricator for compressed air propelled machines the combination of a casing having a lubricant compartment therein, a compressed air conduit having an air travel 35 passageway therein, a pump for pumping lubricant from the lubricant compartment into the compressed air passageway including a grooved spindle extending from the lubricant compartment to a point adjacent 40 said compressed air passageway, and a wheel keyed with the spindle including blades partially extending into the passageway of the compressed air conduit.

3. In a lubricator of the class described 45 the combination of a casing having a lubricant compartment therein, a conduit having a compressed air flow passageway therealong, a grooved spindle extending into the lubricant compartment and toward the compressed air passageway, means substantially 50 enclosing said spindle so that upon rotation thereof oil will be carried therealong within the groove thereof, and means connected with the spindle and extending into the air flow of the compressed air passageway of the conduit whereby incident to air flow the spindle will be rotated to carry lubricant 55 therealong from the lubricant compartment from the lubricant compartment into the air flow passageway.
4. In a lubricator for compressed air propelled machines the combination of a casing having a lubricant compartment therein, an air conduit having a compressed air flow 60 passageway therealong, means formed with said conduit providing a lateral chamber

communicating with the passageway, and pump means rotatably mounted in said lateral chamber extending into the lubricating compartment for withdrawing lubricant therefrom into said chamber, said pump 70 means including a rotary bladed wheel having the blades thereof partially extending into the air flow passageway of said conduit to operate the pump without offering material resistance to the air flow thru said 75 passageway.

5. In a lubricator for compressed air machines the combination of a casing having a lubricant compartment therein, a conduit having an air flow passageway therealong, and pump means operatively connected with the conduit and lubricant compartment for withdrawing oil into the passageway of the air conduit including a rotary bladed operating 80 wheel operating on an axis entirely to 85 one side of the air conduit passageway and including blades partially extending into said air conduit passageway.

6. In a lubricator for compressed air machines the combination of a casing having a lubricant compartment therein, a conduit having an air flow passageway therealong, and pump means operatively connected with the conduit and lubricant compartment for withdrawing oil into the passageway of the air conduit including a rotary bladed operating 90 wheel operating on an axis entirely to 95 one side of the air conduit passageway and including blades partially extending into said air conduit passageway, said blades operating in a plane wholly to one side of the center of said air conduit passageway whereby to offer little resistance to the air flow thru said passageway.

7. In a lubricator for air pressure operated machines the combination of a lubricant receiving casing having a storage reservoir therein, an air conduit having a compressed air flow passageway therealong, means connected with said conduit providing a lateral chamber communicating with said air flow passageway, a spindle having a spiral groove therein, a sleeve rotatably receiving the spindle therein, means mounting the spindle so that a portion of the same extends into said lubricant reservoir and the other portion thereof extends into the lateral chamber communicating with the air passageway, and a bladed member keyed with the spindle having the blades thereof partially extending to the air passageway of 110 115 said conduit.

8. In a lubricator the combination of a unitary housing including a reservoir casing and a conduit having a compressed air flow 120 passageway therealong, a spiral grooved spindle, means rotatably mounting the spiral grooved spindle on an axis substantially at right angles to the axis of the air flow passageway of said conduit, and means con- 125 130

nected with the spindle including a bladed wheel extending into the air flow passageway for rotation by air flow thru said passageway whereby to draw lubricant along said 5 grooved spindle into said air passageway.

9. In a lubricator of the class described the combination of a housing including a lubricant reservoir and a conduit having an air flow passageway therealong, means connected with the conduit providing a lateral compartment communicating with the air passageway thereof, a tubular bushing carried by the housing and extending from the compartment into said lubricant reservoir, 10 a spiral grooved spindle rotatably bearing in said bushing extending into the lubricant of said reservoir and at its opposite end extending into the lateral compartment, and a wheel keyed on the spindle in said lateral 15 compartment having blades thereof partially extending radially into the air passageway of said conduit, said wheel and bushing being so related with the spindle that upon rotation of the spindle oil will be drawn 20 along the groove thereof for flow into the air passageway of conduit.

10. In a lubricator of the class described the combination of a housing including a lubricant reservoir and a conduit having an air flow passageway therealong, means connected with the conduit providing a lateral compartment communicating with the air passageway thereof, a tubular bushing extending from the compartment into said 25 lubricant reservoir, a spiral grooved spindle rotatably bearing in said bushing extending into the lubricant of said reservoir and at its opposite end extending into the lateral compartment, a wheel keyed on the spindle in 30 said lateral compartment having blades thereof partially extending radially into the air passageway of said conduit, and means providing an anti-friction bearing between the bushing and wheel to take the axial 35 thrust of said spindle incident to lift of lubricant from the reservoir to the air passageway of said conduit.

11. In a lubricator of the class described the combination of a housing including a lubricant reservoir and an air conduit having a compressed air flow passageway therealong, means formed with the conduit providing a lateral chamber communicating with the air passageway of the conduit, said 40 means having an opening therein, pump means for the housing detachably insertable thru the opening of said last mentioned means into assembled relation with respect to the reservoir and air passageway for drawing lubricant from the reservoir into the air passageway, and a movable clamp for said opening of said means to detachably clamp the pump in place.

12. In a lubricator of the class described 45 the combination of a lubricant casing hav-

ing a lubricant compartment therein, an air conduit having an air flow passageway therealong above the lubricant compartment, means connected with said conduit providing a lateral chamber communicating 70 with the air passageway, a duct being provided between said chamber and the lubricant compartment to equalize air pressure between the lubricant compartment and air passageway, a bushing mounted in communicating relation between the lubricant compartment and lateral chamber on an axis laterally of the air passageway, a spirally grooved spindle rotatably mounted in said bushing having an end thereof projecting into the lubricant compartment, a sleeve carried by the bushing held stationary thereby and laterally enclosing the lower end of said grooved spindle to enable the lift of lubricant in the groove of said spindle upon rotation of the spindle in said sleeve, the upper end of said spindle projecting into the lateral chamber above mentioned, and a wheel keyed on the upper end of said spindle operating on an axis entirely laterally 85 of the air passageway of said conduit and including blades partially extending into said air passageway entirely to one side of the center thereof.

13. In a lubricator of the class described, 90 a lubricant casing having a reservoir therein, a casing having a way therein along which an impelling fluid travels, and a motor for drawing lubricant from the casing into the way of the other casing including a spindle having spiral grooves arranged in opposed relation, and a wheel having blades disposed in said way for operation by said impelling fluid.

14. In a lubricator for compressed air machines the combination of a conduit having a passageway for flow of compressed air for the machine, a casing having a lubricant receiving compartment therein, a communicating passageway being provided between the conduit passageway and the lubricant compartment, and pump means for drawing lubricant from the compartment into the compressed air passageway including a bladed member rotatably extending into said conduit passageway for operation by the air traveling therealong, and means connected with the bladed member extending through the communicating passageway between the lubricant compartment and conduit passageway for withdrawing oil from the lubricant compartment into the conduit passageway upon rotation of the bladed member.

15. In a lubricator of the class described 125 the combination of a lubricant casing having a lubricant compartment therein, an air conduit having an air flow passageway therealong, bushing means mounted in communicating relation between the lubricant

compartment and the air passageway, a spirally grooved spindle rotatably mounted in said bushing means having an end thereof projecting into the lubricant compartment 5 and the opposite end thereof extending exteriorly of the lubricant compartment, a wheel keyed on the last mentioned end of the spindle having blades located in the air conduit passageway for operation by air 10 travel therealong to rotate said wheel and consequently said spindle, and bearing means between the bushing means and bladed wheel to space the latter from the former to permit flow of lubricant from the 15 spiral groove of the spindle through said space and into the air passageway.

16. In a lubricator of the class described the combination of an air conduit having an air passageway therealong, a casing pro-

viding a lubricant compartment, said conduit having a transverse opening therein communicating with the air passageway, a detachable pump adapted to be inserted through said transverse opening and including a rotary wheel with blades extending 20 into the air passageway, and means connected with the wheel extending into the lubricant compartment for withdrawing oil therefrom into the air passageway upon rotation of said wheel, and detachable bearing means for the transverse opening of said conduit engaging against said pump to hold the same in place, said detachable bearing means when removed from the transverse opening exposing the opening to permit 30 bodily removal of said pump.

LAWRENCE P. MARCELL.
